[57] CLAIM

The ornamental design for a “rubber pad for crutch”, as shown and described.

DESCRIPTION

FIG. 1 is a perspective view of the rubber pad for crutch leg showing my new design;

FIG. 2 is a bottom perspective view thereof;

FIG. 3 is a bottom plan view thereof;

FIG. 4 is a front elevation thereof, of which the rear elevation is a mirror image;

FIG. 5 is a right side elevation thereof, of which the left side elevation is a mirror image; and,

FIG. 6 is a top plan view thereof.
